(57) **CLAIM**

The ornamental design for a “beverage bottle,” as shown and described.

DESCRIPTION

FIG. 1 is a perspective view of a beverage bottle from the left and slightly above, showing my new design;

FIG. 2 is a top plan view thereof;

FIG. 3 is a front side view thereof;

FIG. 4 is a bottom plan view thereof;

FIG. 5 is a left side view thereof, the right side being the mirror image thereof; and,

FIG. 6 is a rear side elevation view thereof.
